CLAIM

The ornamental design for a partition panel, as shown and described.

DESCRIPTION

FIG. 1 is a perspective view of a partition panel showing my new design;

FIG. 2 is a front view thereof, a rear view thereof being a mirror image;

FIG. 3 is a top view thereof;

FIG. 4 is a partial enlarged view thereof, taken along line 4 of FIG. 1;

FIG. 5 is a partial enlarged view thereof, taken along line 5 of FIG. 2; and,

FIG. 6 is a cross-sectional view thereof, taken along the line 6-6 in FIG. 5.

The broken lines shown in the drawings illustrate portions of the partition panel that form no part of the claimed design. The dash-dot lines shown in the drawings define the bounds of the claimed design that form no part of the claimed design.
